(57) CLAIM

The ornamental design for a lawn mower, as shown and described.

DESCRIPTION

FIG. 1 is a front perspective view of a lawn mower taken from the front and one side;

FIG. 2 is a top view thereof;

FIG. 3 is a side elevational view thereof, taken from the side illustrated in FIG 1;

FIG. 4 is a side elevational view thereof, take from the side opposite that illustrated in FIG 1;

FIG. 5 is a front elevational view thereof; and,
FIG. 6 is a rear elevational view thereof.

The views not shown do not constitute part of the claimed design.

It will be understood that the broken lines shown throughout the drawings are for illustrative purposes only and form no part of the subject invention.
